(57) **CLAIM**

The ornamental design for a toy lock, as shown and described.

DESCRIPTION

FIG. 1 is a perspective view of a toy lock, showing my new design;

FIG. 2 is a perspective view thereof, in an alternative configuration;

FIG. 3 is a front elevation view of FIG. 1; the rear elevation view being a mirror image thereof;

FIG. 4 is a left side elevation view of FIG. 1; the right side elevation view being a mirror image thereof;

FIG. 5 is a top plan view of FIG. 1; and,

FIG. 6 is a bottom plan view of FIG. 1.

The broken lines illustrate portions of the toy lock that form no part of the claimed design.
